Primary Examiner—Louis S. Zarfas**Attorney, Agent, or Firm—Sterne, Kessler, Goldstein & Fox****[57] CLAIM**

The ornamental design for a shoe sole, as shown and described.

DESCRIPTION

FIG. 1 is a bottom plan view of a shoe sole showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a left side elevational view of a shoe sole showing an alternate embodiment of my new design;

FIG. 7 is a right side elevational view thereof;

FIG. 8 is a front elevational view thereof;

FIG. 9 is a rear elevational view thereof; and

FIG. 10 is a bottom plan view thereof.

The broken line showing of a shoe upper in the figures is environmental only and forms no part of the claimed design.
